Rudolph Hoffman
Kane Hudson Kent Atty.

UNITED STATES PATENT OFFICE

RUDOLPH HOFFMAN, OF CLEVELAND, OHIO

GRID

Application filed October 26, 1925. Serial No. 64,743.

This invention relates to grids or grates for use in connection with stove tops, and the like, and has for one of its objects the provision of a simple form of construction that will have the requisite strength and durability, to provide a maximum amount of open space for the passage of the hot gases from the burner of the stove and will also be adapted for production at a very low cost.

Other objects of the invention and the features of novelty will be apparent from the following description taken in connection with the accompanying drawings, of which:

Fig. 1 is a perspective view of a stove top having two forms of my invention applied thereto;

Fig. 2 is a plan view of one of the forms of the invention shown in Fig. 1;

Fig. 3 is a plan view of the other form of the invention shown in Fig. 1; and

Fig. 4 is a perspective view of the outer end of one of the supporting arms.

Referring to the drawings, 10 indicates a stove top such as is commonly used in connection with oil and gas stoves and 11 a circular burner opening therein. Burner openings, such as the opening 11, are usually formed with a downwardly extending reinforcing flange 12. The form of my invention shown in connection with the opening 11, and in Fig. 3, consists of a plurality of U-shaped members 13, symmetrically arranged about a center, with their base portions in contacting relation as indicated at the points 14. The members 13, when assembled as shown in Fig. 3, are permanently secured together, at the points 14, by welding or riveting or in any other suitable manner so as to form a unitary structure. Each of the outwardly projecting arms of the members 13 is notched, as shown at 15, in Fig. 4, so that the horizontal edges of these notches may rest on the top 10 and the vertical edges of the notches fit against the flange 12 and thus locate the grid in the opening 11.

In the form of the invention illustrated in Fig. 2, I provide a central ring 16 about which the U-shaped members 17 are symmetrically arranged, these members, contacting with the ring 16 at the point 18 and being there se-

cured by welding, riveting or otherwise. The form shown in Fig. 2 is shaped to fit the rectangular opening 19 in the stove top 10, the U-shaped members 17 having legs of different length to accommodate the grid to this form of opening, it being understood that by having these legs of the same length, as shown in Fig. 3, the structure would be adapted for a circular opening, such as the opening 11.

The members 13 and 17, as well as the ring 16, are preferably made from bars of wrought metal, of rectangular cross-section, commonly called strap-iron, as this form of material may be readily bent, to form the U-shaped members and by bending the bars, as shown in the drawings, a structure of maximum strength and affording the maximum amount of open space is provided.

Having thus described my invention, what I claim is:

1. A grate formed of four uniform U-shaped members symmetrically arranged about a central opening with their base portions connected together, each of said members being formed from a bar of substantially rectangular cross-section.

2. A grate formed of four uniform U-shaped members symmetrically arranged about a central point, and having legs of unequal length, a ring arranged between the inner ends of said members, and the bases of said members being secured to said ring.

3. A grate formed of four uniform U-shaped members symmetrically arranged about a central point and having legs of unequal length, a ring arranged between the inner ends of said members, and the bases of said members being secured to said ring, and said ring and said members being formed from a bar of substantially rectangular cross-section.

4. A grate bar for oil and gas stoves and the like, comprising a plurality of metal bars each having a curved portion intermediate of its ends thereby providing arms extending from the said curved portion and each bar being so bent so as to stand on edge, and a ring to the outer side of which the curved portion of each of said bars is directly con-

nected in such a position that the arms thereof extend in substantially radial directions.

5. A grate for oil and gas stoves and the like, comprising a plurality of metal bars each having a curved portion intermediate of its ends thereby providing arms extending from the said curved portion with each bar bent so as to stand on edge, and a ring to the outer side of which the curved portion of each of the said bars is directly connected in 10 such a position that the arms of the said bars extend in substantially radial directions, the arms of the said bars on the same side thereof being notched at their extremities to be 15 adapted to fit within a support flange provided therefor in the top of an oil or gas stove.

6. A grate for oil and gas stoves and the like, comprising a plurality of metal bars of 20 rectangular cross section each bent intermediate of its ends to provide a curved portion therein and to cause the bar to stand on edge with the arms thereof extending radially from the curved portion, a ring made of a 25 metal bar of rectangular cross section formed to stand on edge, the curved portions of the said bars being permanently connected to the outer side of the said ring in such positions that the arms of the said bars extend 30 in substantially radial directions therefrom.

In testimony whereof, I hereunto affix my signature.

RUDOLPH HOFFMAN.
